UNITED STATES PATENT OFFICE.

DANIEL B. DIMICK, OF BIRMINGHAM, ALABAMA.

APPARATUS FOR CASTING PIPE.

No. 880,284.

Specification of Letters Patent.

Patented Feb. 25, 1908.

Application filed April 25, 1907. Serial No. 370,285.

To all whom it may concern:

Be it known that I, DANIEL B. DIMICK, a citizen of the United States, residing at Birmingham, in the county of Jefferson and 5 State of Alabama, have invented certain new and useful Improvements in Apparatus for Casting Pipe; and I do hereby declare the following to be a full, clear, and exact description of the invention, such as will enable 10 others skilled in the art to which it appertains to make and use the same.

This invention relates to improvements in an apparatus for casting pipe and, as distinguished from the apparatus now in vogue 15 in which the pipe is cast on end with the bell up and in a dry mold, it consists in the mechanism disclosed and wherein green sand may be used instead of dry sand, if desired, and wherein the pipe is molded bell down.

20 While I do not limit myself to the exact details shown and described, for the purposes of disclosure reference is had to the accompanying drawings, illustrating a preferred embodiment of the invention, in which like letters designate the same parts in the several views, and in which:—

Figure 1 is a view in elevation of the assembled apparatus, with the pattern in position before withdrawal. Fig. 2 is a longitudinal 30 section through the mold on the line of joinder of the segmental cope indicated at 2—2, Fig. 3 but omitting the vertical sprue rods shown in Fig. 6. Fig. 3 is a plan view. Fig. 4 is a bottom view. Fig. 5 is a fragmentary detail view, showing the manner of applying the centering ring and also showing a slightly modified form of sectional bell pattern, and Fig. 6 is a longitudinal sectional view through the mold members in their 40 positions preparatory to casting, and showing a slightly modified form of the apparatus, a portion of the hinged cope being shown in elevation.

a designates a hollow drag having the base 45 board *b* mounted on the skids *c*, the base board *b* being provided on its upper face with an annulus *d* and a turret or hollow projection *e*, which turret or hollow projection *e* is provided at its upper end with inwardly extending lugs *f* alining with similarly disposed lugs *g* carried centrally of the base-board *b* which is apertured centrally, as at *h*.

The flask *i* coöperating to form the hollow central core of the mold is preferably of conical shape a portion of its length slightly

tapering from a position substantially at the top of the turret *e*, and from that position downwardly the flask *i* is cylindrical in cross section to snugly fit around the turret or hollow projection *e* and supported at its lower 60 end within the annulus *d*, as clearly shown in Fig. 2.

j designates the bell portion of the pattern and is of segmental construction, being preferably formed of three sections. Of course 65 this bell portion of the pattern may be formed for different designed bells, but for the purpose of illustrating a method of forming bells with grooves therein to make a cement joint, the bell portion of the pattern 70 illustrated in Fig. 2 is provided with an inner face plate *k* having annular grooves there-around.

l designates the pattern for the length of the pipe and consists of the usual cylindrical member provided with a beveled tongue at its lower end adapted to seat within the beveled recess in the upper end of the bell portion of the pattern to form a snug joint, as at *m*. 75

n designates a stripping plate in the form of an annular ring provided with inwardly disposed grooved lugs *o* adapted to aline with the lugs *f* and *g* when the stripping plate *n* is placed in position on top of the 85 flask *i* so that tie bolts *p* passing through the flask and base board will pass through said slotted lugs and securely hold the several parts locked in position. The external circumference of this stripping plate *n* is such 90 as to be just contained within the pipe pattern *l*.

q designates a cope which is formed in two sections, being provided with a top flange *r* and vertical flanges *s*, the vertical flanges *s* 95 being adapted to be secured together in any suitable way. In the drawings (Figs. 2 and 3) this is illustrated by bolt holes and bolts.

On the sides adjacent the vertical flanges, the cope is provided with the curved portions *t* which together form the swells *u* (Fig. 3). The segmental portions of the cope are also provided with brackets which may be cast thereon, comprising the vertical supports *v* and the transverse webs *w*, which 105 webs are enlarged centrally over the vertical portions *v* and are apertured to receive the vertical rods *x* supported in tapered sockets formed in the enlarged portions *y* on the base board of the drag. The horizontal flange *r* 110

of the cope is also provided with central enlarged portions z apertured to receive the upper end of the vertical guiding rods x .

1 designates a second stripping plate 5 which consists of an annular ring, the inner circumference of which is of such a diameter as to just contain the pipe pattern l , and this annular stripping plate 1 is provided with a depending annular portion 2 to afford a 10 deeper guiding surface for the pipe pattern l when being withdrawn, and particularly to form the mold cavity for the spigot ring of the pipe. This stripping plate 1 is also provided with a plurality of fingers 3 projecting 15 from its external circumference and adapted to rest on the top flange r of the cope and to be secured thereto in any suitable manner.

In the drawings for the purpose of illustration, the method of securing these fingers 20 to the cope flange r is by means of U-shaped clips 4.

In the construction previously illustrated, is set forth the broad conception of the invention, which, however, may be improved as to 25 matters of details in many ways. For instance in Fig. 5, as a means for centering the bell portion of the pattern there is illustrated a centering ring comprising the annular member 5 recessed internally to form the 30 upper and lower bearing faces 6 and 7, the base of the centering ring being in the form of a spider having the projecting ends 8 provided with apertures 9 therein, which apertures are arranged to aline with the two 35 tapering sockets formed in the enlarged portions y of the drag, the spider or centering ring being firmly secured in position on said drag through the medium of two headed pins 10 passing through the apertures 8 of the 40 spider and the apertures in the enlarged portion y of the drag. By this arrangement the segmental bell portion of the pattern can be centered and held securely in its assembled position. In Fig. 5 there is also shown a 45 slight modification in the form of the bell portion of the pattern comprising an annular concave recess, whereby the bell portion of the central core of the mold will be of convex shape, the pipe when cast containing a 50 concave annular recess instead of a plurality of annular grooves as before described, this recess being particularly adapted for use in cementing the spigot end of the pipe in the bell portion of the adjacent section.

55 In Fig. 6 a still further modification is illustrated, embodying a more practical form of the invention, as demonstrated by actual use. In this construction, the drag consists of the baseboard as heretofore described and 60 illustrated at 11 which is provided with the annular side wall 12 having the upper flange portion 13 on which rests the cope.

Integrally formed with the base 11 is the turret member 14 recessed at its upper end

as at 15 to receive the conical flask member 65 16 in such manner that the flask member may be readily detached from the supporting turret when desired. At the upper end of the turret the same is provided with the internal lugs 17 slotted as at 18 to receive the 70 headed tie bolts 19 extending upwardly through the flask 16 and secured to corresponding and alining inwardly projecting slotted lugs 20 extending internally of the center stripping ring 21. In this construction the 75 cope member 22 is substantially the same as heretofore described with the exception that instead of being secured by bolts or in other ways, the sections of the same are illustrated as being hinged together as at 23 and secured 80 together at the other edge when in their assembled position by suitable clips 24. In this construction as in that previously described guide rods are employed corresponding to the guide rods x and indicated on this 85 view at 25.

Having thus described the construction of the various parts of the apparatus and referring particularly to Figs. 1 to 4, in assembling the parts preparatory to forming the 90 finished mold, the flask i is placed in position upon the turret or central projection e with its lower end resting within the annulus d . The hollow drag a is then filled with sand and after thorough ramming the sand is cleaned 95 off flush with the top of the drag, as illustrated by the dotted line at 5 in Fig. 2. Upon this smooth surface the bell portion j of the pattern is assembled, being centered in any suitable manner, as for instance by a 100 centering ring as previously described with reference to Fig. 5, which centering ring will also keep the segments from being rammed out of place. The bell portion of the pattern is then filled with sand, and after thorough 105 ramming the sand is again smoothed off at a level with the turret and the top of the bell portion of the pattern. The barrel portion of the pattern is then placed in position and sand is then poured in the annular space between the flask i , and the barrel portion of the pattern l and thoroughly rammed up to the top of the flask. The centering ring 5 (Fig. 5) may now be removed. A layer of 110 parting sand is now placed on that portion of the rammed sand exterior of the bell portion of the pattern and the vertical guide rods x having been placed in position in the sockets formed at y on each side of the drag, the cope 115 is lowered into position, the guide rod passing through the apertured enlarged portions formed on the cope, as before described. The space between the outside of the pattern and the cope is then filled with sand and thoroughly rammed up to the top of the cope. During 120 this latter operation, sprue rods are supported within the swelled portions u of the cope as hereinafter more fully described 125

with reference to Fig. 6 so that the rods may be withdrawn, forming vertical sprue gates for receiving the molten metal when casting.

The ramming having been completed and 5 the cope secured in place, the stripping plate *n* is now placed in position, as shown in Fig. 2, and securely bolted in place by the rods *p*. Similarly, the outer stripping plate 1 is placed in position and securely affixed to the 10 cope by the clips 4, as heretofore described. The barrel portion *l* of the pattern is then drawn out by means of any suitable power, the stripping plates *n* and 1 serving to guide the pattern to make a perfect draw. The 15 whole cope is then lifted off, the guiding rods *x* serving to keep it free from the walls of the inside core. The bell portion of the pattern being now exposed and being segmental in construction, the sections are removed laterally, the grooves in the face plate *k* preventing 20 vertical movement of the bell pattern. Horizontal gates are then cut in the sand to align with the mold chamber and the vertical gates heretofore referred to when the outer 25 core is again placed in position. The vertical sprue gate and the horizontal sprue gate, are hereinafter designated at 27 and 28, respectively, with respect to Fig. 6. The core and outer section of the mold having 30 been properly coated in any well known way and suitably dried with hot air, the cope and the outer mold member are lowered into place over the central core, being still guided by the vertical guide rods *x*, when a suitable 35 chill plate is lowered over the top of the mold. The parts having thus been assembled, the molten metal is poured from the top into the mold, by means of the vertical sprue gate, see Fig. 6, formed on the side 40 within the swelled portion of the cope, the metal flowing upwardly until it strikes the chill plate.

Referring to Fig. 6, the operation is substantially similar. The pattern having been 45 withdrawn, the mold members having been prepared and the outer mold member replaced in position, the tapered sprue rod 26 may now be withdrawn if this has not already been done, leaving the longitudinal 50 vertical sprue gate 27 communicating with the horizontal gate 28 which in this view is cut in the base sand instead of in the outer core member. In this view also a core 29 is shown located at the base of the horizontal 55 gate 28 and on this core the metal falls in passing into the mold cavity 30. This will prevent the cutting away of the base sand by the falling metal, and the feature may or may not be employed, as desired.

60 An important feature of the construction shown in Fig. 6 is the construction and manner of mounting the conical flask 16. By the arrangement shown, it will be obvious that the tie bolts 19 being released, the 65 tapered flask may readily be pulled out as

soon as the pipe is cast and this allows the walls of the mold to give way as the casting contracts in cooling, thus preventing the pipe from developing a crack caused by internal stress.

In practice there is some difficulty, in the ordinary construction of molds, in easily extracting the casting owing to the fact that the mold becomes very hard in drying out, so that it is necessary that the casting be 70 worked out of the mold with considerable difficulty. Another advantageous feature of Fig. 6 therefore resides in providing a hinged connection between the sectional cope members, and these hinges allow the 75 cope to open through an angle of about 90 degrees.

The operation of removing the cope and preparing the mold members is the same as that previously described, the guide rods 25 85 being employed to guide the cope in being removed from and replaced around the core member, but of course after the members have been set ready for casting and it is desired to open up the cope, it is necessary that 90 at least one of the rods be removed in order to enable one of the cope sections to swing on its hinges.

It will also be understood that the combined drag, bottom board and turret are 95 integral and remain permanently in position, that is to say they are not rolled over, the sand being simply struck off and slicked up at the level of the top of the drag from day to day, avoiding the necessity of ramming the 100 base sand after each operation.

As stated in the object of the invention, I may use in this apparatus either dry sand molds or green sand molds. As is well known to those skilled in the art, it has heretofore been impossible to successfully cast pipe sections in green sand molds. I am enabled to accomplish this most desirable result, by the simple expedient of first drawing out my pattern between the stripping plates shown, and then lifting off the cope. This entirely obviates the necessity of dry sand cores, together with the great delay and expense involved in drying or baking the same. Furthermore, the use of green sand 115 instead of dry sand, allows the core barrel to be removed quite easily, if it is done immediately after casting, and as soon as the iron has set in the mold. As is well known to those skilled in the practice of this art, it is 120 very difficult indeed, and often impossible to get a core barrel out, quickly and expeditiously, when dry sand is used. Dry sand, therefore, consumes time, and restricts the output, whereas by the use of green sand, I 125 have experienced no difficulty, and have actually produced in practice a greater output than I anticipated. Therefore, I regard the structure by which I am enabled to use green sand, and also that by which I am en- 130

abled to withdraw my casting practically as soon as it sets, as important features of my invention.

I do not of course wish to be understood as limiting my invention to the precise details of construction and operation as above set forth, since it is obvious that the same may be considerably varied without departing from the spirit of my invention.

10 Having thus described the invention what I claim is:—

1. In apparatus for preparing a mold for casting hollow articles, the combination of means for forming the core member and an outer mold member around a sectional pattern, with a stripping plate, to aid in withdrawing the pattern, and means for securing the same on top of said core within the said pattern, substantially as described.

20 2. In apparatus for preparing a mold for casting hollow articles, the combination with a base support, of means for forming a core and an outer mold member said means comprising a sectional pattern, a stripping plate, to aid in withdrawing said pattern, and other

means for securing said stripping plate on said core within said pattern, said other means comprising tie rods passing through said core and securing said stripping plate to said base support, substantially as described.

30 3. In apparatus for preparing a mold for casting hollow articles, the combination of means for forming a core and outer mold member said means comprising a sectional pattern, an annular stripping ring, to aid in withdrawing said pattern, and other means for securing said stripping ring on top of said mold member in substantial engagement with the exterior of the said pattern, substantially as described.

40 4. In apparatus for preparing a mold for casting pipe, the combination of means for forming a core and outer mold member said means comprising a sectional pattern, having a barrel portion, a stripping ring to aid in withdrawing said pattern provided adjacent its inner circumference with a depending annular portion, and means for securing said stripping ring on the top of said outer mold member with said annular depending portion in substantial engagement with the exterior of the barrel portion of said pattern to form the spigot of the mold, substantially as described.

50 5. In apparatus for preparing a mold for casting pipe, the combination with means for forming a core and outer mold member comprising an element a sectional pattern, having a barrel portion, a cope, a stripping plate and means for securing the same on said core within the barrel portion of said pattern, an external stripping ring surrounding the outer barrel portion of said pattern, and means for securing the same to said cope

on top of said outer mold member, substantially as described.

6. In apparatus for preparing a mold for casting pipe, the combination with a base support, a flask carried thereby, a sectional pattern, an internal stripping plate and means for securing the same on said flask, and an external stripping plate, and means for securing the same on said cope, substantially as described.

7. In apparatus for preparing a mold for casting pipe, the combination with a drag carrying a turret member centrally thereof, a flask mounted adjacent said turret member, a stripping plate mounted on said flask, a sectional pattern, and a stripping plate mounted around said sectional pattern at the upper end thereof, substantially as described.

8. In an apparatus for preparing a mold for casting pipe, the combination of a drag, a turret member carried thereby, and a tapering flask member detachably mounted on said turret member, substantially as described.

9. In an apparatus for preparing a mold for casting pipe, the combination of a drag, a turret member carried thereby, and a tapering flask member detachably mounted on said turret member, and a pattern surrounding said flask member, substantially as described.

10. In an apparatus for preparing a mold for casting pipe, the combination of a drag, a turret formed integral therewith, a tapering flask mounted on said turret member, means detachably securing said flask and turret member together, comprising a tongue and groove connection therewith, and a pattern surrounding said flask member, substantially as described.

11. In an apparatus for preparing a mold for casting pipe, the combination of a drag, a turret member formed integral therewith and comprising a cylindrical projection provided with internally disposed slotted lugs at the upper end thereof, a tapering flask member mounted on said turret member, and means for detachably securing the same together, a centrally apertured stripping plate mounted on said flask member and provided with internally disposed projecting slotted lugs, aligning with said first mentioned slotted lugs, tie rods connecting said

opposed slotted lugs together, a pattern surrounding said flask and stripping plate, a cope, a stripping ring surrounding said pattern and provided with an annular depending portion, and means for securing said stripping ring to said cope with said annular depending portion in engagement with the exterior of said pattern, substantially as described.

12. In an apparatus for preparing a mold

for casting pipe, the combination with a drag provided with a pair of apertures, a sectional bell pattern provided with an irregular interior face, means for holding said sectional pattern in position, comprising a centering ring resting on said drag and additional means for centering the said sectional pattern, substantially as described.

13. In an apparatus for preparing a mold for casting pipe, the combination with a drag, provided with a pair of apertures, a sectional bell pattern provided with an irregular interior face, means for holding said sectional pattern in position, comprising a centering ring apertured to aline with the apertures, in said drag and headed pins passing through said apertures, substantially as described.

14. In an apparatus for preparing a mold for casting pipe, the combination with a drag, provided with a pair of apertures, a sectional bell pattern provided with an irregular interior face, means for holding said sectional pattern in position, comprising a centering ring apertured to aline with the apertures in said drag and headed pins passing through said apertures, and an upper pattern section surmounting said bell pattern, substantially as described.

15. In an apparatus for preparing a mold for casting pipe, the combination of a drag provided with a turret member formed integral therewith, a tapering flask member superposed on said turret member, a sectional pattern, and a cope member supported on said drag and comprising a pair of hinged sections, substantially as described.

16. In an apparatus for preparing a mold for casting pipe, the combination of a drag provided with a turret member formed integral therewith, a tapering flask member superposed on said turret member, a sectional pattern, and a sectional cope member supported on said drag comprising a pair of

hinged sections and means for centering said sectional pattern, substantially as described. 45

17. In apparatus for preparing a mold for casting pipe, the combination with a hollow drag, a central flask therefor, a sectional bell pattern, a barrel pattern, a cope having swelled portions and provided on opposite sides with guiding means and also provided with an external top flange, guiding rods carried by said drag engaging said guiding means, a stripping plate centrally apertured and provided with inwardly extending lugs, 55 means for securing said stripping plate on top of said flask within the barrel portion of the pattern, comprising tie rods connecting said lugs with said hollow drag, an external stripping plate comprising a ring having an 60 annular downward projection and laterally disposed fingers, and fastening means engaging the top flange of said cope and said fingers, substantially as described.

18. In an apparatus for making molds for casting pipe in green sand molds, the combination of a suitable cope, a flask, a pattern provided with a barrel portion and stripping plates on each side of the barrel portion of said pattern, substantially as described. 65

19. In an apparatus for making molds for casting pipe the combination of a cope provided with apertured enlarged portions and made in sections provided with swells at their meeting edges, said sections hinged together 75 and adapted to be lifted vertically, with the long guide rods *k*, fitting in said apertured portions and serving to guide the cope when lifted, substantially as described.

In testimony whereof, I affix my signature, in presence of two witnesses. 80

DANIEL B. DIMICK.
